UNITED STATES PATENT OFFICE.

WILLIAM F. BOUCHÉ, OF BUFFALO, NEW YORK, ASSIGNOR TO GOULD COUPLER COMPANY, A CORPORATION OF NEW YORK.

DYNAMO SUSPENSION.

1,241,492.

Specification of Letters Patent.

Patented Oct. 2, 1917.

Application filed June 18, 1915. Serial No. 34,865.

To all whom it may concern:

Be it known that I, WILLIAM F. BOUCHÉ, a citizen of the United States, and a resident of Buffalo, county of Erie, State of New York, have invented certain new and useful Improvements in Dynamo Suspensions, of which the following is a specification.

My invention relates to improvements in arrangements for supporting dynamos on car trucks. One object of my invention is to provide a simple and efficient arrangement or structure, having few parts, easily constructed and put together and so arranged that they do not interfere with other apparatus on the car. Further objects, features and advantages will more clearly appear from the detailed description given below, taken in connection with the accompanying drawings, which form a part of this specification.

In the drawings Figure 1 is a plan view of a portion of the car truck with my improvements in one form arranged thereon. Fig. 2 is an end view of parts shown in Fig. 1. Fig. 3 is a section taken on the line 3—3 of Fig. 1. Fig. 4 is a side view of parts shown in Figs. 1 and 2. Fig. 5 is a detail looking in the direction of arrows 5—5 of Fig. 1. Fig. 6 is a detail side view of one of the sliding supporting blocks, from which the generator or dynamo is pivotally suspended. Fig. 7 is a view looking in the direction of the arrows 7—7 of Fig. 6. Fig. 8 is a section taken on the line 8—8 of Fig. 6. Fig. 9 is a plan view of parts shown in Fig. 6. Fig. 10 is a perspective illustrating the arrangement of the axle pulley on the axle.

Referring to the various figures, 1 represents a car truck having side sills 2, a depressed end sill 3, safety sills 4 suitably carried upon the car axles, one of which is shown at 5, provided with the usual car wheels 6. Rigidly secured to the truck, adjacent the side sills 2 and extending outwardly, horizontally from the truck, are two parallel supporting bars 7, one on each side of the truck. At their outer ends these bars are bent backwardly at 8 and secured to the outside of the truck by bolts 9. The rearwardly extending portions of these bars have bar portions 10, which for a short distance extend parallel to the outwardly extending bars 7. Upon one set of the parallel

extending bars 7, 10, is arranged a sliding block 11, adjustable longitudinally of the bars 7, 10, provided with upwardly extending ears 12, through which passes a pivot bolt 13, surrounded by a bearing bushing 14, 60 so arranged that the bolt 13 oscillates with the members or portions 30 hereinafter referred to, (see Figs. 6 to 9). The block 11 is also provided on each side with downwardly extending ears 15, which are securely 65 clamped to the parallel bars 7, 10, by means of screw bolts 16 and lock nuts 17. Intermediate the bars 7 and 10, the block 11 is provided with integral spacing webs 18, each provided with a reinforcing rib 20. 21 70 and 22 represent two hooks, the hook 21 engaging about the underneath side of the bar 10 and the hook 22 engaging about the underneath side of the bar 7. The shanks of these hooks extend upwardly through 75 the block 11 and are secured thereto by means of nuts 23 and lock nuts 24.

By loosening the hooks 21 and 22 and the clamping bolts 16, block 11 is adjustable longitudinally of the bars 7 and 10, and 80 upon tightening up of the screw bolts 16 and hooks 21 and 22, the block 11, which slidably rests upon the bars 7 and 10, may be secured in its adjusted position.

Carried upon the other pair of parallel 85 bars 7 and 10 is a block 25, provided with similar upwardly extending ears 26, carrying a similar pivot bolt 27 and surrounding bearing bushing. The block 25 is likewise provided with similar integral spacing webs 90 and reinforcing ribs 18 and 20 (not shown in connection with block 25). The block 25, however, is provided with ears 28 extending downwardly, two on the inside of the bar 7 and two on the outside of the bar 10, and bolts 29 pass through the inner and outer ears respectively and bars 7 and 10, in order to firmly and non-adjustably secure the block 25 to the bars 7 and 10. Pivotally supported by the blocks 11 and 25 and 100 about the pivot bolts 13 and 27 is a swinging V-shaped member, having downwardly extending parts or portions 30, and a base or horizontal cross portion 31 on which a dynamo 32 is non-adjustably secured, by 105 means of clamping plates 33. The downwardly extending portions 30 at the upper part thereof are each bent rearwardly toward the truck 2 and thence they are inclined inwardly toward the dynamo 32, as at 110

34 (see Figs. 2, 3 and 4). Extending between the downwardly extending portions 30, but above the base or cross piece 31, is a cross-bar 35, formed of an angle iron, and 5 at each end clamped to the portions or parts 30 by means of clamping plates 36. A plate 37 has one end secured to the angle cross bar 35 at 38, and at its other end is bent over to the shape of the dynamo 32 and 10 apertured to accommodate an integral lug 39 on the dynamo 32. The plate 37 is bolted to the top of the dynamo by means of bolts 40. In this way the dynamo 32 is rigidly secured to the swinging member, comprising 15 downwardly extending portions 30 and base 31, the dynamo being supported on base 31 in such position that the axis of the pivots 13 and 27 lies substantially directly over the axis of the dynamo, so that the center of 20 gravity of the swinging parts lies substantially directly beneath the pivotal axis. The dynamo is provided with a pulley 41 and the axle with a pulley 42 and a belt 43 passes over these pulleys, for the purpose 25 of driving the dynamo from an axle 5 of the truck.

In order that the pulleys 41 and 42 may be brought into proper alignment, the pulley 42 is adjustable along the axle 5. To this 30 end the pulley 42 is made in two halves and provided with a two piece bushing 44, as shown in Fig. 10. When it is desired to adjust the pulley to a different position on the axle 5, in order to bring it into proper alignment with the pulley 41, the clamping bolts, which clamp the two sections of the pulley 42 together, are loosened and the pulley, with its bushing, is then moved to the desired position on the axle 5, whereupon it is 35 then clamped in the proper adjusted position.

For the purpose of alining the axis of the dynamo to bring it parallel with the car axle, the hooks 21 and 22 are loosened, as 40 well as the screw bolts 16, and the block 11 is then adjusted longitudinally of the bars 7, 10, until the axis of the dynamo is 45 parallel with the car axle, whereupon the hooks 21 and 22 and bolts 16 are again made to firmly clamp block 11 in place on the bars 7 and 10.

A cross bar 50 rigidly connects the outer ends of the supporting bars 7. Cross bar 50 is preferably made of a piece of angle 50 iron and has a centrally depressed portion 51. Carried by and coöperating with the centrally depressed portion 51 is a tension device, comprising a link 52, passing through an aperture in the vertical web of the angle 55 cross bar 50 and pivotally connected to the cross bar 35, at 53. On its outer end the link 52 is surrounded by coil spring 54, compressed thereon against the bar 50 by means of a hand nut 55, so that upon operating 60 the hand nut 55, the tension with which the

spring 54 tends to move the dynamo away from the truck and keep the belt taut, may be adjusted. By arranging the end sill 3, cross bar 50 with centrally depressed portions, and arranging the bar 35, so that it 70 does not extend above the depressed portion of bar 50, there are no parts of the arrangement which interfere with the center beams of the car or other devices secured thereto at this point. 75

Lug 39 on the dynamo is provided with an aperture through which extends a pin 60 provided with cotters in each end, pin 60 being outside of the end of plate 37. In case bolts 40 should fail to hold the dynamo 80 rigid with plate 37, the lug 39 and pin 60 will maintain the dynamo in position and this acts as a safety device.

It will be seen that the dynamo is easily accessible at all parts thereof, and is easily 85 removed for repairs. To remove the dynamo it is only necessary to remove the cap plates 31 and the bolts at 38, or the bolts at 40 and pin at 60, when the dynamo may be readily slipped off the support at 31, the belt 90 43 being removed.

While I have described my improvements in great detail and with respect to the preferred embodiment thereof, nevertheless, I do not desire to be limited to such details 95 except as clearly pointed out in the appended claims, as many changes and modifications may well be made without departing from the spirit and scope of my invention in its broader aspects. 100

What I claim as new and desire to secure by Letters Patent is:

1. An arrangement of the class described, having in combination with a car truck, supporting bars extending from the truck, 105 means for pivotally suspending a dynamo from said bars, a depressed cross member connecting the outer ends of said bars, means for driving the dynamo from an axle of the truck, and a tension device carried by 110 said cross member and tending to swing the dynamo away from the axle.

2. An arrangement of the class described, having in combination with a car truck, two supporting bars extending substantially 115 horizontally from the truck, means for pivotally suspending a dynamo from said bars outside of the truck, a centrally depressed cross member connecting the outer ends of said bars, means for driving the dynamo from an axle of the truck, and a tension device carried at the centrally depressed portion of the cross bar and 120 tending to swing the dynamo away from the axle.

3. An arrangement of the class described, having in combination with a car truck, supporting bars extending from the truck, a swinging V-shaped member pivotally supported at each end by one of said bars re- 125 130

- spectively, a dynamo carried on the base of said V-shaped member and means for driving the dynamo from an axle of the truck.
4. An arrangement of the class described, having in combination with a car truck, supporting bars extending from the truck, a swinging member supported at each end by one of said bars respectively, said member having downwardly extending parts, the upper ends of which are pivotally supported by said bars, said downwardly extending parts being bent rearwardly toward the truck, and a dynamo driven from an axle of the truck supported on the base of said member.
5. An arrangement of the class described, having in combination with a car truck, supporting bars extending from the truck, a swinging member supported at each end by one of said bars respectively, said member having downwardly extending laterally inclined parts, the upper ends of which are pivotally supported by said bars, said downwardly extending parts being bent rearwardly toward the truck, and a dynamo driven from an axle of the truck, supported on the base of said member, the pivotal axis of said member being substantially directly above the axis of the dynamo.
6. An arrangement of the class described, having in combination with a car truck, supporting bars extending from the truck, a swinging member supported at each end by one of said bars respectively, a dynamo supported on said member, said member having downwardly extending portions inclined toward the dynamo, a belt for driving the dynamo from an axle of the truck, and tensioning means tending to keep the belt taut.
7. An arrangement of the class described, having in combination with a car truck, supporting bars extending from the truck, a swinging member supported at each end by one of said bars respectively, said member having a cross part and downwardly extending parts, the upper ends of which downwardly extending parts are pivotally supported by the supporting bars, a dynamo supported on said cross part, a belt driving the dynamo from an axle of the truck and a centrally depressed cross member connecting the outer ends of said supporting bars.
8. An arrangement of the class described, having in combination with a car truck, supporting bars extending from the truck, a swinging member supported at each end by one of said bars respectively, said member having a cross part and downwardly extending parts, the upper ends of which downwardly extending parts are pivotally supported by the supporting bars, a dynamo supported on said cross part, a belt driving the dynamo from an axle of the truck and a centrally depressed cross member connecting the outer ends of said supporting bars,
- and a tension device coöperating with the centrally depressed portion of the cross bar and tending to maintain the belt taut.
9. An arrangement of the class described, having in combination with a car truck, supporting bars extending from the truck, a swinging member supported at each end by one of said bars respectively, said member having a cross part and downwardly extending parts inclined toward the dynamo, the upper ends of which downwardly extending parts are pivotally supported by the supporting bars, a dynamo supported on said cross part, a belt driving the dynamo from an axle of the truck and a centrally depressed cross member connecting the outer ends of said supporting bars, and a tension device coöperating with the centrally depressed portion of the cross bar and tending to maintain the belt taut.
10. An arrangement of the class described, having in combination with a car truck, supporting bars extending from the truck, a swinging member supported at each end by one of said bars respectively, said member having downwardly extending parts, the upper ends of which are pivotally supported by said bars, said downwardly extending parts being bent rearwardly toward the truck, and a dynamo driven from an axle of the truck, supported on the base of said member, a cross bar connecting said downwardly extending parts of the swinging member above its base, and means for securing the upper part of the dynamo to said last mentioned cross bar.
11. An arrangement of the class described, having in combination with a car truck, supporting bars extending from the truck, a swinging member supported at each end by one of said bars respectively, said member having downwardly extending parts, the upper ends of which are pivotally supported by said bars, a cross bar connecting the outer ends of said supporting bars, a dynamo driven from an axle of the truck, supported on the base of said member, a cross bar connecting said downwardly extending parts of the swinging member above its base, and means for securing the upper part of the dynamo to said last mentioned cross bar.
12. An arrangement of the class described, having in combination with a car truck, supporting bars extending from the truck, a swinging member supported at each end by one of said bars respectively, said member having downwardly extending parts, the upper ends of which are pivotally supported by said bars, a cross bar connecting the outer ends of said supporting bars, a dynamo driven from an axle of the truck, supported on the base of said member, a cross bar connecting said downwardly extending parts of the swinging member above

- its base, and means for securing the upper part of the dynamo to said last mentioned cross bar, and a tension device coöperating with said two cross bars.
- 5 13. An arrangement of the class described, having in combination with a car truck, supporting bars extending horizontally from the truck, a swinging member supported at each end by one of said bars 10 respectively, said member having downwardly extending parts, the upper ends of which are pivotally supported by said bars, a cross bar connecting the outer ends of said supporting bars, a dynamo driven from an 15 axle of the truck, supported on the base of said member, a belt for driving the dynamo, a cross bar connecting said downwardly extending parts of the swinging member above its base, and means for securing the upper 20 part of the dynamo to said last mentioned cross bar, and a tension device coöperating with said two cross bars and tending to maintain the belt taut.
14. An arrangement of the class described, having in combination with a car 25 truck, means for pivotally supporting a dynamo from the truck, including two parallel spaced apart bars supported by the truck, a block resting on said bars and adjustable 30 longitudinally thereof, means for pivotally supporting the dynamo from said block, and a hook engaging about one of said bars and having a shank secured to the block for holding the block in adjusted position on 35 said bars.
15. An arrangement of the class described, having in combination with a car truck means for pivotally supporting a dynamo from the truck including two parallel 40 spaced apart bars supported by the truck, a block resting on said bars and adjustable longitudinally thereof, means for pivotally supporting the dynamo from said block, and two hooks, one engaging about each of said 45 bars, said hooks having shanks secured to the block for holding the block in adjusted position on said bars.
16. An arrangement of the class described, having in combination with a car 50 truck, means for pivotally supporting a dynamo from the truck, including two parallel spaced apart bars supported by the truck, a block resting on said bars and adjustable 55 longitudinally thereof, means for pivotally supporting the dynamo from said block and a clamping screw device engaging over the edge of one of said bars for holding the block in adjusted position on said bars.
17. An arrangement of the class described, having in combination with a car 60 truck, means for pivotally supporting a dynamo from the truck including two parallel spaced apart bars supported by the truck, a block resting on said bars and adjustable 65 longitudinally thereof, means for pivotally supporting the dynamo from said block, and a clamping screw device engaging over the edge of one of said bars for holding the block in adjusted position on said bars.
18. An arrangement of the class described, having in combination with a car 70 truck, supporting bars extending from the truck, a swinging member having downwardly extending portions, the upper ends of which are pivotally supported by said bars, a dynamo supported by the base of 75 said swinging member, said downwardly extending portions being inclined toward the dynamo, a pulley on the dynamo, a pulley on an axle of the truck and a belt driving the dynamo pulley from the axle pulley, said 80 axle pulley being adjustable longitudinally of the axle to bring it into alinement with the dynamo pulley.
19. An arrangement of the class described, having in combination with a car 85 truck, supporting bars extending from the truck, a swinging member having downwardly extending portions, the upper ends of which are pivotally supported by said bars, a dynamo supported by the base of 90 said swinging member, a cross bar connecting the downwardly extending portions of said members above its base, means for securing the upper part of the dynamo to said cross member, said downwardly extending 95 portions being inclined toward the dynamo, a pulley on the dynamo, a pulley on an axle of the truck and a belt driving the dynamo pulley from the axle pulley, said axle pulley being adjustable longitudinally of the 100 axle to bring it into alinement with the dynamo pulley.
20. An arrangement of the class described, having in combination with a car 105 truck, supporting bars extending from the truck, a swinging member having downwardly extending portions, the upper ends of which are pivotally supported by said bars, a dynamo supported by the base of 110 said swinging member, said downwardly extending portions being inclined toward the dynamo, a pulley on the dynamo, a pulley on an axle of the truck, and a belt driving the dynamo pulley from the axle pulley, said 115 axle pulley being adjustable longitudinally of the axle to bring it into alinement with the dynamo pulley, a centrally depressed cross bar connecting the outer ends of said supporting bars, and a tension device coöperating with said cross bar to maintain tension on the belt.

In testimony whereof, I have signed my name to this specification.

WILLIAM F. BOUCHE.
